UNITED STATES PATENT OFFICE.

BYRON B. CARTER, OF HINSDALE, AND FRANK J. STRATTON, OF GROSSDALE, ILLINOIS.

MOLDING-MACHINE.

SPECIFICATION forming part of Letters Patent No. 727,900, dated May 12, 1903.

Application filed April 16, 1900. Serial No. 13,011. (No model.)

To all whom it may concern:

Be it known that we, BYRON B. CARTER, a resident of Hinsdale, in the county of DuPage, and FRANK J. STRATTON, a resident of Grossdale, in the county of Cook, State of Illinois, citizens of the United States, have invented an Improved Molding-Machine, of which the following is a specification.

This invention relates to molding-machines. 10 Primary objects of the invention are to provide improved means for actuating the pattern-carrying head and for adjusting the same and to provide simple means for breaking the adhesion between the flask and stripper-plate. 15 A molding-machine of our invention consists of the various features, combinations of features, and details of construction herein-after described and claimed.

In the accompanying drawings a molding-machine of our invention is fully illustrated.

Figure 1 is a rear elevation of a molding-machine of our invention. Fig. 2 is an end view thereof. Fig. 3 is a top plan view thereof, the stripper-plate being removed. Fig. 4 is an enlarged sectional view of the cylinder. Figs. 5, 6, and 7 are enlarged views of the cock which controls the delivery of fluid under pressure to the cylinder, and Figs. 8 and 9 are enlarged detail views.

30 The frame of our improved molding-machine consists of a suitable base A, in which are secured upright rods or standards A', to which the stripper-plate A² is secured in any desired or approved manner. Located beneath the stripper-plate A², and freely movable toward and from said stripper-plate on suitable guides, is the pattern-carrying head B, which, as shown, consists of a plate B', removably secured to a frame B². As shown, 35 the guides for the pattern-carrying head in its movement toward and from the stripper-plate A² are formed by the rods or standards A', to which are fitted suitable bearings in the frame B².

40 B³ represents a pattern supported in operative position on the pattern-plate B'.

As to the foregoing features the construction of our improved molding-machine is old and well known and will be readily and fully 45 understood by a person familiar with the art

from an inspection of the drawings and without a more detailed description thereof.

Movement toward and from the stripper-plate A² is imparted to the pattern-carrying head B by means of suitable operative connection with shafts C, revolvably mounted in the machine-frame. As shown, there are two shafts C, which extend transversely of the machine adjacent to the ends thereof and are connected by means of a rod C', pivotally connected to cranks c, keyed or otherwise rigidly secured to said shafts C. Movement of either shaft will thus impart a corresponding movement to the other, the relation and adjustment of parts being such that the angular movement of said shafts will be the same.

In the preferable construction shown the pattern-carrying head B is connected to the shafts C by means of toggles C², the upper members of which are pivoted to said head, 70 and the lower members of which are keyed to said shafts C. Oscillation of said shafts will thus operate in an obvious manner to flex and straighten said toggles C², and thus to impart movement to said pattern-carrying head B toward and from the stripper-plate A². Formed on the hubs of the lower toggle members are shoulders C³, which project beneath the flange of the base A, forming stops to limit the pivotal movement of the shafts C 80 to positions corresponding to the extreme elevation and depression of the pattern-carrying head. As preferably constructed, also, the rod C' and the upper members of the toggles C² are made in sections connected by 85 turnbuckles c' c², respectively. Provision is thus made for adjusting the relatively angular positions of the shafts C and the lengths of the toggles C² within limits, thus providing means for maintaining the pattern-carrying head B level and for adjusting its extreme elevation.

Our improved machine is adapted to be operated either by hand or by power. The means for operating said machine by hand 95 consist of a hand-lever D, adapted to be detachably engaged with a suitable hole formed in a hub or collar d, rigidly secured to one of the shafts C.

The means for operating the machine by 100

power consist of a motor comprising a cylinder E and a piston E' fitted thereto, the piston-rod E² of which is applied to one of the shafts C, so that reciprocation of said piston 5 will impart an oscillatory movement to said shaft C. In the preferable construction shown the cylinder E is pivoted upon one of the shafts C, and the outer end of the piston-rod E² is pivoted directly to a crank e, secured 10 to the other shaft C. A simple and cheap form of cylinder consists of a section of tube, to the ends of which are secured heads E³ E⁴. The head E³ may and preferably will be soldered or otherwise permanently secured to 15 the cylinder E, and formed thereon is a transverse sleeve e', the bore of which is fitted to the end of the shaft C, thus forming the desired pivotal connection thereto. Said sleeve e' is maintained in position upon said shaft C 20 by a collar e² and a stud-bolt e³, threaded into said shaft. The head E⁴ is removably secured to the cylinder E, being preferably threaded thereto. To maintain a tight joint between the cylinder E and the cylinder-head E⁴, a 25 suitable packing is provided. As shown, said packing consists of what may be designated as a "gasket" E⁵, preferably leather, secured to the inner surface of said cylinder-head, the edges of which project sufficiently 30 to be clamped between the end of the cylinder E and the inner face of said cylinder-head E⁴ when said cylinder-head is secured to said cylinder. As shown, the gasket E⁵ is secured in proper position on said cylinder-head by means of a disk E⁶, bolted to 35 said cylinder-head, between which and said cylinder-head said gasket E⁵ is clamped. Around the piston-rod E² the gasket E⁵ is cupped, as shown at e⁴, a hole being formed 40 in the disk E⁶ sufficiently large to allow fluid under pressure free access to the exterior of the cupped portion e⁴ of said gasket E⁵, thus forming a piston-rod packing. Formed on the cylinder-head E⁴ is a sleeve e⁵, in which 45 is formed the bearing for the piston-rod E², said sleeve being long enough to provide a bearing of desired length for said piston-rod. A shield E⁷, secured to the cylinder-head E⁴, extends over the piston-rod E² and prevents 50 sand from falling thereon during the formation of the mold. In the preferable construction shown the cylinder-ports e⁶ e⁷ are formed directly in the cylinder-heads E³ E⁴.

In practice we prefer to use compressed air 55 for operating our machine; but any other medium, as steam, water, or the like, may be used.

In the preferable construction shown the admission and discharge of fluid under pressure 60 to and from the cylinder E are controlled by means of a suitable cock F, the casing of which comprises four branches f' f² f³, which communicate with the bore of the casing of said cock in which the plug of said cock is seated 65 through ports or openings f⁴, between which are lands f⁵. Opposite the ports of said cock the plug is cut away, as shown at f⁶ f⁷, in

such manner that the ports to the branches f' f³ may be brought into communication with the ports to the branches f f² by properly rotating the plug of said cock, the relation and adjustment of parts being such that when the port to the branch f is in communication with the port to the branch f' the port to said branch f' will be cut off from the port to the branch f², while the port to the branch f³ will be in communication with the port to the branch f² and will be cut off from the port to the branch f, and vice versa. The ports to the branches f' f³ are not designed to communicate with each other at any time. Stops f⁸ on the casing of the cock project into the path of travel of a lug f⁹ on the plug of the cock and operate to limit the pivotal movement thereof, one extreme position of said plug 85 effecting full communication of the port to the branch f' with the port to the branch f and of the port to the branch f³ with the port to the branch f², and the other extreme position of said plug effecting full engagement of the 90 port to the branch f with the port to the branch f³ and of the port to the branch f' with the port to the branch f². The plug of said cock F is operated by means of a hand-lever F', secured to the end thereof. 95 The branch f of the cock F is connected with a source of supply of fluid under pressure. (Not shown.) The branch f² is the discharge or exhaust branch thereof. The branches f' f³ are respectively connected with 100 the ports e⁶ e⁷ of the cylinder E. As shown, the connections between said cock F and the cylinder-ports comprise pipes f¹⁰, which extend to the end of the machine, and flexible tubes f¹¹, which connect said pipes f¹⁰ 105 with the branches f' f³ of the cock F. In the preferable construction shown also the cock F is secured to the pattern-carrying head B in position such that the hand-lever F' may be conveniently grasped by the machine operator. The flexible connections f¹¹ provide for 110 desired vertical movement of the pattern-carrying head B and for pivotal movement of the cylinder E without wrenching the connections between said cock F and the cylinder E. 115 Preferably, also, a petcock F² is secured in the discharge or exhaust branch f² of the cock F, thus providing convenient means for regulating the size of the discharge-opening 120 and the escape of the fluid from the cylinder E in order to prevent the pattern-carrying head from being raised or lowered too rapidly under the influence of the fluid under pressure admitted to said cylinder.

Buffer-springs G, inserted between the pattern-carrying head B and the base A of the machine, and preferably around the rods or standards A' as guides, operate in a familiar manner to stop the pattern-carrying head B gradually as it approaches the lower limit of its movement, thus preventing jarring and shock to the parts of the machine. Said springs G are made sufficiently strong to raise the pattern-carrying head B and the parts

carried thereon through a portion of its travel independently of the toggles C². Said springs will thus operate in an obvious manner to prevent said toggles from becoming locked should they be flexed at too great an angle.

As illustrated, a section H of a flask, either the drag or the cope, is supported upon the stripper-plate A², being secured in operative position thereon by dowel-pins h in the usual manner. As preferably constructed our improved molding-machine comprises means for slightly raising the section of flask H, as the pattern-carrying head B descends, to break the adhesion between said section of flask and the stripper-plate, thus facilitating the removal of said section of flask. As shown, the means for so raising said section of flask consist of rods H', which are longitudinally movable in suitable bearings formed in the base A of the machine and in the stripper-plate A², the upper ends of which are adapted to be brought into contact with the section of flask H when said rods are raised and the lower ends of which are in the path of travel of projections on the shafts C. As shown, said projections on said shafts C consist of the stop-shoulders C³ on the hubs of the lower members of the toggles C², the relation of parts being such that said stops C³ will strike the lower ends of said rods H' just before the pattern-carrying head B reaches the lower limit of its movement and will raise said rods, so as to lift said section of flask H a desired distance. Pins h', secured in said rods and adapted to rest on a rigid portion of the machine-frame, maintain said rods in operative positions.

We claim—

1. In a molding-machine, the combination of a stripper-plate, a pattern-carrying head, guides on which said pattern-carrying head is movable toward and from said stripper-plate, a shaft or shafts revolubly mounted in the machine-frame, operative connection between said shaft or shafts and the pattern-carrying head whereby rotation of said shaft or shafts will impart movement to said pattern-carrying head toward and from the stripper-plate and means to rotate said shaft or shafts, said means comprising a pivoted cylinder and a piston fitted thereto the piston-rod of which is pivoted to a crank secured to an actuating-shaft, and means under the control of the operator for admitting fluid under pressure to and exhausting it from said cylinder, substantially as described.

2. In a molding-machine, the combination of a stripper-plate, a pattern-carrying head, guides on which said pattern-carrying head is movable toward and from said stripper-plate, a shaft or shafts revolubly mounted in the machine-frame, operative connection between said shaft or shafts and the pattern-carrying head whereby rotation of said shaft or shafts will impart movement to said pattern-carrying head toward and from the stripper-plate and means to rotate said shaft or

shafts, said means comprising a pivoted cylinder, a piston fitted thereto the piston-rod of which is pivoted to a crank secured to an actuating-shaft and a manually-operated valve which controls the admission of fluid under pressure to said cylinder and its exhaust therefrom, substantially as described.

3. In a molding-machine, the combination of a stripper-plate, a pattern-carrying head, guides on which said pattern-carrying head is movable toward and from said stripper-plate, a shaft or shafts revolubly mounted in the machine-frame, operative connection between said shaft or shafts and the pattern-carrying head whereby rotation of said shaft or shafts will impart movement to said pattern-carrying head toward and from the stripper-plate and means to rotate said shaft or shafts, said means comprising a pivoted cylinder, a piston fitted thereto the piston-rod of which is connected to a crank secured to an actuating-shaft, a manually-operated valve and flexible connection between said valve and said cylinder, substantially as described.

4. In a molding-machine, the combination with a stripper-plate, a pattern-carrying head, guides on which said pattern-carrying head is movable toward and from said stripper-plate, means to impart movement to said pattern-carrying head toward and from said stripper-plate, said means comprising toggles applied to said pattern-carrying head and means to flex and straighten said toggles, of stop-shoulders on the hubs of the lower members of said toggles which extend under rigid portions of the machine-frame and lifting-rods longitudinally movable in suitable bearings in the base of the machine-frame and in the stripper-plate, the lower ends of which are in the paths of travel of said stop-shoulders on the hubs of the lower toggle members so as to be raised thereby when the pattern-carrying head reaches the lower limit of its movement, substantially as described.

5. In a molding-machine, a frame having upturned sides to constitute a stripper-plate support, two parallel operating-shafts mounted on the lower part of the frame, adjustable means to rock said shafts in unison in opposite directions; a pattern-carrier vertically slideable on the frame, and connections between the pattern-carrier and the operating-shafts, eccentrically connected with the latter, to raise and lower the pattern-carrier by rocking movement of the operating-shafts, said connections being independent of the means for rocking the shafts.

In testimony that we claim the foregoing as our invention we have hereunto set our hands this 9th day of April, 1900.
